Attorney

UNITED STATES PATENT OFFICE.

JOHN R. NAYLOR AND ALBERT CLARK, OF AKRON, OHIO.

CAME.

Application filed April 8, 1924. Serial No. 704,947.

To all whom it may concern:

Be it known that JOHN R. NAYLOR and ALBERT CLARK, citizen of the United States, and subject of Great Britain, respectively, 5 residing at Akron, in the county of Summit and State of Ohio, have invented certain new and useful Improvements in Cames, of which the following is a specification.

Our invention relates to improvements in 10 cames adapted to be utilized in holding together the panes of glass in art glass windows, skylights, transoms, doors, lamps, vehicle windows and the like.

An object of the invention is to provide 15 a conventional type of lead came having a reinforcing member to rigidly support the panes and prevent distortion and loosening.

A further object of the invention is to provide a came having a concealed reinforcing 20 member to strengthen the came which does not mar its appearance.

Another object of the invention is to provide 25 a device of the above-mentioned character which is simple and durable in construction, efficient in serving its purpose and inexpensive to manufacture.

Other objects and advantages of the invention will be apparent during the course 30 of the following description.

In the accompanying drawing forming a part of this specification and in which like 35 numerals are employed to designate like parts throughout the same,

Figure 1, is a perspective fragmentary 40 view of a window built with our improved came,

Figure 2, is a perspective fragmentary view of the came,

Figure 3, is a perspective fragmentary 45 view of a modified form of reinforcing bar, and

Figures 4, and 5 are perspective fragmentary views showing cames having ornamental designed faces.

In the drawing, wherein for the purpose 50 of illustration, we have shown a preferred embodiment of our invention, the numeral 5 denotes generally the lead came which is H shape in cross section having a web 6 and

55 opposite flanges 7 projecting from the edges of the web to provide longitudinal grooves 8 along the sides. Fitted within the grooves 8 along the sides. Fitted within the grooves

are reinforcing channel bars 9, preferably 55 constructed of brass, copper, zinc or other stiff material. The glass panes 10 are seated in the channel bars and it will be observed that the edges of the flanges 7 extend beyond the edges of the reinforcing bars, being bent inwardly, as at 11, to form a tight fit between 60 the came and pane to exclude dirt and moisture. The web 12 of the channel bars 9 may be straight or curved as clearly illustrated in Fig. 3. The outer face of the came may be horizontal, curved as shown in Fig. 4 or 65 of ornamental design as shown in Fig. 5.

This construction will provide a came having the same appearance as the ordinary lead came, but which is much stronger and durable and which eliminates the use of exterior 70 strengthening means. It may be used for large or small panes and is capable of shaping to fit panes of various designs.

It is to be understood that the form of our 75 invention herewith shown and described is to be taken as a preferred example of the same, and that certain changes in the shape, size and arrangement of parts may be resorted to without departing from the spirit of the invention or the scope of the claims.

Having thus described my invention, I 80 claim:

1. A came for glass panes having a web, oppositely disposed flanges projecting from the edges of the web and channel bars 85 mounted between said flanges the edges of said flanges being bent over the edges of said bars.

2. A lead came having longitudinal 90 grooves and channel bars fitted within said grooves, the flanges of said grooves having their marginal edges bent over the edges of said channel bars.

3. A lead came for glass panes having a web, oppositely disposed flanges extending 95 from the edges of said web, and channel bars seated between the flanges in frictional contact therewith and the web, said flanges having their marginal edges projecting beyond the edges of the channel bars and bent inwardly over the edges of the bars into binding relation with the pane.

In testimony whereof we affix our signatures.

JOHN R. NAYLOR.
ALBERT CLARK.
